MINING MACHINE

Original Filed Aug. 31, 1925 2 Sheets-Sheet 2

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 31, 1925, Serial No. 53,517. Renewed April 24, 1928.

This invention relates to mining machines and more particularly to mining machines of the so-called longwall type in which a machine frame having a cutter bar or other suitable cutter mechanism projecting laterally therefrom is adapted to be drawn longitudinally of a mine working face of substantial length through the cooperation with winding means carried by the machine with the flexible feeding member extending from the machine to a fixed point at a point in advance of the latter.

Among the objects of the present invention is the provision of an improved mining machine and more particularly of an improved longwall mining machine. Another object of the invention is the provision of an improved longwall mining machine of a type adapted to cut in inverted positions with the bar substantially continuing the surface over which the machine moves or at a substantial distance above the mine bottom and working in a dirt band or a similar location. A further object of the invention is to provide an improved feeding mechanism for a longwall mining machine in which a plural speed rotation of a flexible feeding member winding element may be accomplished through simplified mechanism. Other objects and advantages of the invention will subsequently appear.

In a preferred form the invention may comprise a machine frame comprising a cutting mechanism section, an intermediate motor section, and a feeding mechanism section at the opposite side of the motor section from the cutting mechanism section. Preferably the feeding mechanism section comprises a feed operating member adapted to coact with and wind a flexible rope or cable. Said feed operating member is preferably rotatable on a vertical axis approximately midway between the sides of the machine frame and in a position adjacent the front end of the latter and also in horizontal planes including the cutting mechanism. The actuating mechanism for the feed operating mechanism is preferably of the friction-controlled, plural-speed type and preferably comprises planetary gearing having a plurality of coaxial elements, a plurality of which may be driven to effect different coaction thereof to produce different feeding speeds. The driving mechanism for the

planetary gearing preferably comprises a plurality of frictionally controlled trains which drive the planetary gearing through worms and worm gears.

The arrangement of the parts may obviously be substantially varied and for purposes of illustration I have disclosed in the accompanying drawings two specific forms which the invention may assume in practice.

In these drawings,—

Fig. 1 is a view partially in plan and partially in horizontal longitudinal section showing one illustrative form of my invention.

Fig. 2 is a longitudinal vertical section on the line 2—2 of Fig. 1, with parts shown in elevation.

Fig. 3 is a longitudinal vertical section on line 3—3 of Fig. 1.

Fig. 4 is a fragmentary elevational view of a portion of the front end of the machine showing the location of controlling means.

Fig. 5 is a transverse section on the line 5—5 of Fig. 3.

Fig. 6 is a fragmentary plan view of the feeding mechanism end of a modified form of construction, the top plate of the machine being broken away to disclose the internal mechanism.

Fig. 7 is a vertical section on the line 7—7 of Fig. 6.

Taking up first the species of the invention disclosed in Figs. 1 to 5 of the drawings, 1 is an invertible mining machine frame having opposite surfaces 2 and 3 upon either of which it may selectively slide during cutting and other feeding movements. The frame 1 comprises a central motor section 4, the feeding section 5, and the cutting mechanism section 6, and the latter carries a pivotally mounted cutter bar 7 having a circulating cutter chain 8 of usual form. The cutter bar may be moved to different angular positions about a pivotal axis 9 lying in the central longitudinal vertical plane of the machine and may be held in its different adjusted positions by suitable locking means 10. The motor section 4 contains a driving motor 11 having an armature shaft 11^a which is connected in suitable clutch controlled driving relation with the cutter chain 8 and as the details of this mechanism may obviously assume a large

number of forms, no specific illustration has been provided. A form of mechanism which is well adapted for this purpose is disclosed in the copending application of 5 Morris P. Holmes, Serial No. 619,839, filed Feb. 19, 1923, now matured into Patent 1,670,155, patented May 15, 1928. The feeding mechanism section 5 carries in horizontal planes including the cutter bar 7 a vertically journaled rope or cable winding drum 12 upon which a flexible feeding member 13, herein in the form of a flexible wire cable, is adapted to be wound. Drum 12 is journaled on suitable ball bearings 14 surrounding a removable stud 15 held in position upon the machine frame by a bolt 16 which passes through the stud and enters an intermediate partition 17 of the machine frame. The partition 17, a vertical transverse partition 18 and a longitudinal partition 19, together with the external walls of the frame section 5 provide a plurality of chambers 20 and 21 in which suitable controller and rheostat mechanism may be 25 located.

The front end of the armature shaft 11^a is elongated and is journaled in a bearing 22 and in the spaced bearing 23. At opposite sides of the bearing 23, a plurality of 30 driving pinions 24 and 25 are arranged. The pinions 24 and 25 respectively mesh with and constitute driving elements for a pair of larger spur gears 26 and 27 each of which is journaled for rotation about the 35 axis of the horizontal longitudinally extending shaft 28. The shaft 28 is journaled in four longitudinally spaced bearings 30, 31, 32 and 33, two or more of which may be thrust bearings as well as bearings supporting the shaft for rotation upon its axis. The bearing 33 is supported upon a removable section 34 carried by the transverse partition 18, this construction being employed to facilitate the removal of the shaft 28. 40 The gear 26 is provided with a bearing portion 35 which is freely rotatable upon the periphery of a sleeve 36 which is keyed as at 37 to the shaft 28. The gear 26 and the sleeve 36 are provided with portions respectively engaging alternate friction clutch discs 38 and 39 and the gear 26 also provides an abutment portion 40 against which the discs may be pressed by a slidable pressure applying member 41 which is mounted 45 upon a sleeve 42 mounted upon the shaft 28 adjacent the bearing 31. Loading of the friction clutch including the discs 38 and 39 will connect the gear 26 with the sleeve 36 and so effect driving of the shaft 28. 50 The gear 27 is provided with a bearing portion 43 journaled upon a sleeve member 44 which is loose upon the shaft 28 and carries a clutch disc engaging portion 45. The latter is arranged coaxially with a co- 55 operating clutch disc engaging portion 46

carried by the gear 27, and series of friction clutch disc elements 48 and 49 are respectively engaged by the portions 45 and 46 and held in non-rotative relation thereto. Suitable pressure applying means including 70 the pressure applying plate 50 having fingers 51 engaging the end disc 49 is adapted to effect frictional engagement of the discs 48 and 49 and cause rotation, upon driving of the gear 27, of the sleeve 44. Permanently clutched by clutch teeth 52 to the sleeve 44 is a spur pinion 54 which meshes with and drives a spur gear 55 which is rigidly secured to a shaft 56. The shaft 56 is journaled in a bearing 57 and in a bearing 59 corresponding to the bearing 33 and removable in a similar manner. The shaft 28 carries a driving worm 60 and the shaft 56 a driving worm 61, the pitch of these worms being determined by the desired speeds and their direction being determined by the desired direction of rotation of the feed operating member. 80

The rope winding drum 12 carries an internal gear 65 which is driven by a driving pinion 66 rotatable upon a vertical axis disposed rearwardly of the axis of rotation of the drum and adapted to be driven at different speeds by the two worms 60 and 61. Supporting and actuating mechanism for the gear 66 is as follows: Supported upon a removable cover plate 67 and in a bearing 68 carried thereon is a shaft 69 having a flange 70 engaging the inner race of the bearing 68. A worm wheel 71 is keyed as at 72 to the upper end of the shaft 69 and is journaled in the bearing 68. Rotatably mounted upon the periphery of the shaft 69 below the worm wheel 71 and upon anti-friction bearings 73 is a sleeve portion 74 of a worm wheel 75. The worm wheel 75 is a planet carrier and has mounted therein a plurality of stud shafts 76 surrounded by bearings 77 upon which planet gears 78 are rotatable. 90 Adjacent its lower end the shaft 69 has mounted thereon a spur pinion 80 which meshes with the several planet gears 78. The lower end of the shaft 69 is journaled in a bearing 81 supported in the upper end of a sleeve member 82 which is bolted as at 83 to a yoke member 84 secured at its opposite ends to the dividing plate 17 and doweled to the latter. Surrounding the sleeve member 82 and rotatable upon bearings 86 is a sleeve portion 87 which is provided externally with the teeth 66 and carries an internal gear 88 which is engaged by the planet gears 78. The partition 19 is provided with an opening 89 within which the internal gear 88 rotates, this gear being a close running fit for the opening to prevent the access of dust or other injurious material to the gearing. The worm 61 drives the worm wheel 71, the worm 60 driving the worm wheel 75. 100 110 115 120 125 130

The clutch discs 38, 39 and 48, 49 may be

forced into frictional engagement by any suitable mechanisms. Herein hand-wheels 89 and 90 control the rotation of longitudinally immovable threaded rods 91 and 92 which engage nuts on the free ends of clutch loading levers. Referring to Fig. 5, the rod 91 will be noted to be engaged in a nut 93 carried in trunnions at the free end of a lever 94 pivoted as at 95 and at its opposite ends having roller equipped clutch loading fingers 96. The mechanism for controlling the other clutch is generally similar.

At its end remote from the cutter bar are guide sheaves 98 and 99 adjacent opposite sides of the frame and a central guide sheave 100.

The mode of operation of the first form of the invention may now be described. As is well known, rotation of the central gear of the epicyclic train of the type disclosed while the planet carrier remains stationary causes rotation in the opposite direction of the internal gear which forms the outside member of the gear train, while bodily rotation of the planet carriers with the central pinion stationary causes rotation of the internal gear in the same direction as the direction of rotary movement of the planet carrier. As there is a reverse in the direction of rotation of the two worms effected by the presence of the pinion 54 and gear 55, it will be evident that since it is desired that the drum rotate in the same direction at both the slow and fast speeds the worms will be similarly threaded, but in order to provide for a speed of rotation of the drum suitable for the moving speed, the worm 60 engaging with the worm wheel 75 is given a considerably steeper pitch than the worm 61. It will now be evident that in moving the machine to a desired position the elements 24 and 26 may be caused to effect drive of the shaft 28 and so of the worm 60 with resultant relatively rapid rate of rotation of the drum 12. During cutting, however, the members 25 and 27 may serve to drive through the pinion 54 and gear 55 the worm 61 with the resultant considerably slower rate of rotation. A third speed can be obtained by causing both worms to rotate at the same time and variations secured by slipping the clutches. It is unnecessary to go into details as to the manner in which the bar is swung under the coal, this being done in any usual manner by the employment of a flexible feeding member. It should be noted, however, that the flexible feeding member may be led off over either side of the machine about the guide sheaves provided and that different speeds of rotation of the feed operating member can be obtained by allowing the clutches controlling the driving of the worms to slip to different extents.

Next referring to Figs. 6 and 7, another embodiment of the invention may be ob-

served. Here it will be noted that illustration of the cutting end of the machine is entirely omitted, this mechanism being the same as in the previous form. The forward end of a motor armature shaft 14^a carries a driving pinion 24^a which is arranged intermediate a pair of driven gears 26^a and 27^a which are respectively provided with friction clutch mechanisms analogous to that associated with the gear 26 in the species first described and generally designated 101^a and 101^b, these friction clutch mechanisms serving to connect the gears 26^a and 27^a respectively in driving relation to shafts 28^a and 56^a. The shaft 28^a carries a worm 60^a while the shaft 56^a carries a worm 61^a. Suitable bearings shown in elevation at 30^a and 59^a are provided for the shafts 28^a and 56^a. A rope winding drum 12^a corresponding to the drum 12 is journaled on the frame in a position much nearer to the motor than in the form shown in Figs. 1 to 5, and this drum is provided with an internal gear 65^a corresponding to the internal gear 65. Mechanism corresponding closely in construction with the parts 67 to 88 is provided for actuating a driving pinion 66^a and the general method of control and operation is very similar to that previously described. In view of the rotation in like directions of the gears 26^a and 27^a and the arrangement of the worm 60^a and 61^a at opposite sides of the axis of rotation of the pinion 66^a the worms are provided with opposite threads but otherwise the construction, except as of the general arrangement mentioned, is extremely like that of the first species described. It is therefore believed that it is unnecessary to provide any further description of the mode of operation of this mechanism than to say that the fast feed is obtained by the drive through the gear 26^a while the slow feed is obtained through the gear 27^a and that variations in speeds may be obtained as in the first form described.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a motor, a feed operating member rotatable on a vertical axis, and means for transmitting power from said motor to said member including a plurality of coaxial members, two of which support coaxial gear members and another of which supports planet devices meshing with said gear members, means for effecting rotation of two of said members by power from

said motor to effect drive of the other including driving trains of which the other member forms no part, and means connecting the other of said members in driving relation to said feed operating member whereby it may drive the latter.

2. In a mining machine, a motor, a feed operating member rotatable on a vertical axis, and means for transmitting power from said motor to said member including a plurality of coaxial members, two of which support coaxial gear members and another of which supports planet devices meshing with said gear members, means for effecting rotation of two of said members at different speeds by power from said motor to effect drive of the other including driving trains of which the other member forms no part, and means connecting the other of said members in driving relation to said feed operating member whereby it may drive the latter.

3. In a mining machine, a motor, a feed operating member rotatable on a vertical axis, and means for transmitting power from said motor to said member including a plurality of coaxial members, two of which support coaxial gear members and another of which supports planet devices meshing with said gear members, means for effecting rotation of two of said members in opposite directions by power from said motor to effect drive of the other including driving trains of which the other member forms no part, and means connecting the other of said members in driving relation to said feed operating member whereby it may drive the latter.

4. In a mining machine, a motor, a feed
operating member rotatable on a vertical
axis, and means for transmitting power from
said motor to said member including a plu-
rality of coaxial members, two of which sup-
port coaxial gear members and another of
which supports planet devices meshing with
40 said gear members, means for effecting rota-
tion of two of said members in opposite di-
rections at different speeds by power from
said motor to effect drive of the other in-
cluding driving trains of which the other
45 member forms no part, and means connect-
ing the other of said members in driving
relation to said feed operating member
whereby it may drive the latter.

55 5. In a mining machine, a motor, a feed
operating member rotatable on a vertical
axis, and means for transmitting power
from said motor to said member including a
plurality of coaxial members, two of which
support coaxial gear members and another
of which supports planet devices meshing
with said gear members, means for effecting
rotation of two of said members separately
or together by power from said motor to
effect drive of the other including driving

trains of which the other member forms no part, and means connecting the other of said members in driving relation to said feed operating member whereby it may drive the latter.

6. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members by power from said motor to effect drive of the other including driving trains of which the other member forms no part, and means connecting the other of said members in driving relation to said feed operating member whereby it may drive the latter. 85 75

7. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members at different speeds by power from said motor to effect drive of the other including driving trains of which the other member forms no part, and means connecting the other of said members in driving relation to said feed operating member whereby it may drive the latter. 90 95 100

8. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members in opposite directions by power from said motor to effect drive of the other including driving trains of which the other member forms no part, and means connecting the other of said members in driving relation to said feed operating member whereby it may drive the latter.

9. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members in opposite directions at different speeds by power from said motor to effect drive of the other including driving trains of which the 120 125 130

other member forms no part, and means connecting the other of said members in driving relation to said feed operating member whereby it may drive the latter.

5 10. In a mining machine, a motor, a feed operating member, and means for transmitting power from said motor to said member including a plurality of coaxial members having their axes in a vertical line, two of 10 which support coaxial gear members and another of which supports planet devices meshing with said gear members, means for effecting rotation of two of said members separately or together by power from said motor to effect drive of the other including driving trains of which the other member forms no part, and means connecting the other of said members in driving relation to said feed operating member whereby it 20 may drive the latter.

11. In a mining machine, a motor, a feed operating member rotatable on a vertical axis, and means for transmitting power from said motor to said member including 25 a plurality of coaxial members, two of which support coaxial gear members and another of which supports planet devices meshing with said gear members, means for effecting rotation of two of said members 30 by power from said motor including worms rotating on parallel axes, and means connecting the other of said members in driving relation to said feed operating member.

12. In a mining machine, a motor, a feed 25 operating member rotatable on a vertical axis, and means for transmitting power from said motor to said member including a plurality of coaxial members, two of which support coaxial gear members and another 40 of which supports planet devices meshing with said gear members, means for effecting rotation of two of said members at different speeds by power from said motor including worms rotating on parallel axes, and means 45 connecting the other of said members in driving relation to said feed operating member.

13. In a mining machine, a motor, a feed 50 operating member rotatable on a vertical axis, and means for transmitting power from said motor to said member including a plurality of coaxial members, two of which support coaxial gear members and another of which supports planet devices meshing with 55 said gear members, means for effecting rotation of two of said members in opposite directions by power from said motor including worms rotating on parallel axes, and means connecting the other of said members in driving relation to said feed operating member.

60 14. In a mining machine, a motor, a feed operating member rotatable on a vertical axis, and means for transmitting power from 65 said motor to said member including a plu-

rality of coaxial members, two of which support coaxial gear members and another of which supports planet devices meshing with said gear members, means for effecting rotation of two of said members in opposite directions at different speeds by power from said motor including worms rotating on parallel axes, and means connecting the other of said members in driving relation to said feed operating member.

70 15. In a mining machine, a motor, a feed operating member rotatable on a vertical axis, and means for transmitting power from said motor to said member including a plurality of coaxial members, two of which support coaxial gear members and another of which supports planet devices meshing with said gear members, means for effecting rotation of two of said members separately or together by power from said motor including worms rotating on parallel axes, and means connecting the other of said members in driving relation to said feed operating member.

75 16. In a mining machine, a motor, a feed 80 operating member, and means for transmitting power from said motor to said member including a plurality of coaxial members having their axes in a vertical line, two of which support coaxial gear members and another of which supports planet devices meshing with said gear members, means for effecting rotation of two of said members by power from said motor including worms rotating on parallel axes, and means connecting the other of said members in driving relation to said feed operating member.

85 17. In a mining machine, a motor, a feed 90 operating member, and means for transmitting power from said motor to said member including a plurality of coaxial members having their axes in a vertical line, two of which support coaxial gear members and another of which supports planet devices meshing with said gear members, means for effecting rotation of two of said members by power from said motor including worms rotating on parallel axes, and means connecting the other of said members in driving relation to said feed operating member.

95 18. In a mining machine, a motor, a feed 100 operating member, and means for transmitting power from said motor to said member including a plurality of coaxial members having their axes in a vertical line, two of which support coaxial gear members and another of which supports planet devices meshing with said gear members, means for effecting rotation of two of said members at different speeds by power from said motor including worms rotating on parallel axes, and means connecting the other of said members in driving relation to said feed operating member.

105 19. In a mining machine, a motor, a feed 110 operating member, and means for transmitting power from said motor to said member including a plurality of coaxial members having their axes in a vertical line, two of which support coaxial gear members and another of which supports planet devices meshing with said gear members, means for effecting rotation of two of said members in opposite directions by power from said motor including worms rotating on parallel axes, and means connecting the other of said members in driving relation to said feed operating member.

19. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members in opposite directions at different speeds by power from said motor including worms rotating on parallel axes, and means connecting the other of said members in driving relation to said feed operating member. 65
- 15 20. In a mining machine, a motor, a feed operating member, and means for transmitting power from said motor to said member including a plurality of coaxial members having their axes in a vertical line, two of which support coaxial gear members and another of which supports planet devices meshing with said gear members, means for effecting rotation of two of said members separately or together by power from said motor including worms rotating on parallel axes, and means connecting the other of said members in driving relation to said feed operating member. 75 80

and means connecting the other of said members in driving relation to said feed operating member.

28. In a mining machine, a motor, a feed 5 operating member, and means for transmitting power from said motor to said member including a plurality of coaxial members having their axes in a vertical line, two of which support coaxial gear members and 10 another of which supports planet devices meshing with said gear members, means for effecting rotation of two of said members in opposite directions by power from said motor including worms rotating on parallel axes 15 extending longitudinally of said machine, and means connecting the other of said members in driving relation to said feed operating member.

29. In a mining machine, a motor, a feed 20 operating member, and means for transmitting power from said motor to said member including a plurality of coaxial members having their axes in a vertical line, two of which support coaxial gear members and 25 another of which supports planet devices meshing with said gear members, means for effecting rotation of two of said members in opposite directions at different speeds by power from said motor including worms rotating on parallel axes extending longitudinally 30 of said machine, and means connecting the other of said members in driving relation to said feed operating member.

30. In a mining machine, a motor, a feed 35 operating member, and means for transmitting power from said motor to said member including a plurality of coaxial members having their axes in a vertical line, two of which support coaxial gear members and 40 another of which supports planet devices meshing with said gear members, means for effecting rotation of two of said members separately or together by power from said motor including worms rotating on parallel 45 axes extending longitudinally of said machine, and means connecting the other of said members in driving relation to said feed operating member.

31. In a mining machine, a motor, a feed 50 operating member, and means for connecting said motor to said feed operating member to drive the latter including epicyclic reduction gearing disposed with its axis of orbital movement vertical and in the central longitudinal vertical plane of the machine, and 55 means including a plurality of worms rotating on axes extending longitudinally of said machine for actuating a plurality of elements of said epicyclic gearing to produce a plural speed operation of said feed operating member.

32. In a mining machine, a motor, a feed 60 operating member, and means for connecting said motor to said feed operating member to drive the latter including epicyclic reduction 65

gearing disposed with its axis of orbital movement vertical and in the central longitudinal vertical plane of the machine, and means including a plurality of frictionally controlled worms rotating on axes extending 70 longitudinally of said machine for actuating a plurality of elements of said epicyclic gearing to produce a plural speed operation of said feed operating member.

33. In a mining machine, a motor, a feed 75 operating member rotating on an axis in the central longitudinal vertical plane of said machine, and means for connecting said motor to said feed operating member to drive the latter including epicyclic reduction gearing disposed with its axis of orbital movement vertical and in the central longitudinal vertical plane of the machine, and means including a plurality of worms rotating on axes extending longitudinally 80 of said machine for actuating a plurality of elements of said epicyclic gearing to produce a plural speed operation of said feed operating member.

34. In a mining machine, a motor, a feed 85 operating member rotating on an axis in the central longitudinal vertical plane of said machine, and means for connecting said motor to said feed operating member to drive the latter including epicyclic reduction 90 gearing disposed with its axis of orbital movement vertical and in the central longitudinal vertical plane of the machine, and means including a plurality of worms rotating on axes extending longitudinally 95 of said machine for actuating a plurality of elements of said epicyclic gearing to produce a plural speed operation of said feed operating member.

35. In a mining machine, a motor, a feed 100 operating member rotating on a vertical axis in the central longitudinal vertical plane of said machine, and means for connecting said motor to said feed operating member to drive the latter including epicyclic reduction 105 gearing disposed with its axis of orbital movement vertical and in the central longitudinal vertical plane of the machine, and means including a plurality of worms rotating on axes extending longitudinally 110 of the machine for actuating a plurality of elements of said epicyclic gearing to produce a plural speed operation of said feed operating member.

36. In a mining machine, a motor, a feed 115 operating member rotating on a vertical axis in the central longitudinal vertical plane of said machine, and means for connecting said motor to said feed operating member to drive the latter including epicyclic reduction 120 gearing disposed with its axis of orbital movement vertical and in the central longitudinal vertical plane of the machine, and means including a plurality of worms rotating on 125 frictionally controlled worms rotating on 130

axes extending longitudinally of said machine for actuating a plurality of elements of said epicyclic gearing to produce a plural speed operation of said feed operating member.

37. In a mining apparatus, a machine frame having a projecting cutter bar, a feed operating member rotatable on an axis perpendicular to the plane of said bar, a driving member therefor rotatable on an axis parallel to the axis thereof, and driving means for said driving member including a worm rotatable on an axis extending longitudinally of said frame and a friction clutch coaxial 15 with said worm through which the latter is driven.

38. In a mining apparatus, a machine frame having a projecting cutter bar, a feed operating member rotatable on an axis perpendicular to the plane of said bar, a driving member therefor rotatable on an axis parallel to the axis thereof, and plural speed driving means for said driving member including a worm rotatable on an axis extending longitudinally of said frame and a friction clutch coaxial with said worm through which the latter is driven.

39. In a mining machine, a machine frame having at one end thereof a pivoted cutter chain carrying cutter bar and at the opposite end thereof a feed operating member rotatable on a vertical axis midway between the sides of the machine frame, a motor intermediate said bar and said feed operating member and adapted to actuate said cutter chain, and operative connections between said motor and said feed operating member including a gear rotatable on an axis extending longitudinally of said machine frame, a friction clutch coaxial therewith, and a worm rotatable on loading of said clutch and coaxial with said gear.

40. In a mining machine, a machine frame having at one end thereof a pivoted cutter chain carrying cutter bar and at the opposite end thereof a feed operating member rotatable on a vertical axis midway between the sides of the machine frame, a motor intermediate said bar and said feed operating member and adapted to actuate said cutter chain, and operative connections between said motor and said feed operating member including a driving pinion carried by said motor, a gear meshing therewith and constantly driven thereby and rotatable on an axis extending longitudinally of said machine frame, a worm coaxial with said gear, a worm wheel rotatable on a vertical axis and driven by said worm, driving connections between said worm wheel and said feed operating member, and clutch devices for connecting said worm and gear whereby the latter may drive the former.

41. In a mining machine, a machine frame having at one end thereof a pivoted cutter

chain carrying cutter bar and at the opposite end thereof a feed operating member rotatable on a vertical axis midway between the sides of the machine frame, a motor intermediate said bar and said feed operating member and adapted to actuate said cutter chain, and operative connections between said motor and said feed operating member including a driving pinion carried by said motor, a gear meshing therewith and constantly driven thereby and rotatable on an axis extending longitudinally of said machine frame, a worm coaxial with said gear, a worm wheel rotatable on a vertical axis and driven by said worm, driving connections between said worm wheel and said feed operating member, and friction clutch devices for connecting said worm and gear whereby the latter may drive the former.

42. In a mining machine, a machine frame having at one end thereof a pivoted cutter chain carrying cutter bar and at the opposite end thereof a feed operating member rotatable on a vertical axis midway between the sides of the machine frame, a motor intermediate said bar and said feed operating member and adapted to actuate said cutter chain, and operative connections between said motor and said feed operating member including a driving pinion carried by said motor, a gear meshing therewith and constantly driven thereby and rotatable on an axis extending longitudinally of said machine frame, a worm coaxial with said gear, a worm wheel rotatable on a vertical axis midway between the sides of the machine frame and driven by said worm, driving connections between said worm wheel and said feed operating member, and clutch devices for connecting said worm and gear whereby the latter may drive the former.

43. In a mining machine, a machine frame having at one end thereof a pivoted cutter chain carrying cutter bar and at the opposite end thereof a feed operating member rotatable on a vertical axis midway between the sides of the machine frame, a motor intermediate said bar and said feed operating member and adapted to actuate said cutter chain, and operative connections between said motor and said feed operating member including a driving pinion carried by said motor, a gear meshing therewith and constantly driven thereby and rotatable on an axis extending longitudinally of said machine frame, a worm coaxial with said gear, a worm wheel rotatable on a vertical axis midway between the sides of the machine frame and nearer said motor than the axis of rotation of said feed operating member and driven by said worm, driving connections between said worm wheel and said feed operating member, and clutch devices for connecting said worm and gear whereby the latter may drive the former.

44. In a mining machine, a machine frame having at one end thereof a pivoted cutter chain carrying cutter bar and at the opposite end thereof a feed operating member 5 rotatable on a vertical axis midway between the sides of the machine frame and adapted to cooperate directly with flexible feeding means, a motor intermediate said feed operating member and said bar and adapted 10 to actuate said cutter chain, an actuating member for said feed operating member rotating on a vertical axis nearer said motor than the axis of rotation of said feed operating member, and worm driving gearing 15 for said actuating member including a plurality of coaxial friction clutches.

45. In a mining machine a machine frame having at one end thereof a pivoted cutter chain carrying cutter bar and at the opposite 20 end thereof a feed operating member rotatable on a vertical axis midway between the sides of the machine frame and adapted to cooperate directly with flexible feeding means, a motor intermediate said feed operating member and said bar and adapted to 25 actuate said cutter chain, an actuating member for said feed operating member rotating on a vertical axis nearer said motor than the axis of rotation of said feed operating member, and worm driving gearing for said 30 actuating member including a plurality of coaxial friction clutches arranged with their axes extending longitudinally of said machine frame.

46. In a mining machine, a machine frame having at one end thereof a pivoted cutter chain carrying cutter bar and at the opposite end thereof a feed operating member 40 rotatable on a vertical axis midway between the sides of the machine frame and adapted to cooperate directly with flexible feeding means, a motor intermediate said feed operating member and said bar and adapted to 45 actuate said cutter chain, an actuating member for said feed operating member rotating on a vertical axis nearer said motor than the axis of rotation of said feed operating member, and worm driving gearing for said 50 actuating member including a plurality of coaxial friction clutches arranged with their axes extending longitudinally of said machine frame and including a fast feed clutch adjacent said motor and a slow speed clutch further from said motor.

47. In a mining machine, a machine frame having at one end thereof cutting mechanism, intermediate its ends a motor, and at its other end a feed operating member rotatable on a vertical axis and adapted to 60 operate directly with flexible feeding means, and means driven by said motor for effecting rotation of said feed operating member including a worm rotating on a horizontal axis and friction controlled driving means 65 for said worm comprising a plurality of ele-

ments connecting the same with said motor and all of which rotate on stationary axes parallel to a line parallel to the worm axis.

48. In a mining machine, a motor, cutting mechanism driven thereby, and feeding 70 means driven by said motor including a feed operating member rotatable on a vertical axis and adapted to cooperate with flexible feeding means, and driving means for said feed operating member including oppositely rotatable coaxial worm gears disposed on vertical axes. 75

49. In a mining machine, a motor, cutting mechanism driven thereby, and feeding 80 means driven by said motor including a feed operating member rotatable on a vertical axis and adapted to cooperate with flexible feeding means, and driving means for said feed operating member including oppositely rotatable coaxial worm gears disposed on vertical axes and operative to drive 85 said feed operating member at a plurality of speeds.

50. In a mining machine, a motor, cutting mechanism driven thereby, and feeding 90 means driven by said motor including a feed operating member rotatable on a vertical axis and adapted to cooperate with flexible feeding means, and driving means for said feed operating member including oppositely rotatable coaxial worm gears disposed on vertical axes and operative to drive 95 said feed operating member at a plurality of speeds in the same direction.

51. In a mining machine, a motor, cutting 100 mechanism driven thereby, and feeding means driven by said motor including a feed operating member rotatable on a vertical axis and adapted to cooperate with flexible feeding means, and driving means for 105 said feed operating member including worms rotatable on parallel horizontal axes and coaxially arranged worm gears meshing with said worms.

52. In a mining machine, a motor, cutting 110 mechanism driven thereby, and feeding means driven by said motor including a feed operating member rotatable on a vertical axis and adapted to cooperate with flexible feeding means, and driving means 115 for said feed operating member including coaxially arranged worm gears rotatable on vertical axes and in opposite directions, and parallel longitudinally extending horizontal worms meshing with said worm gears. 120

53. In a mining machine, a horizontal motor having its axis extending longitudinally of the machine, cutting mechanism driven from one end of said motor, and feeding mechanism driven from the opposite 125 end of said motor including a feed operating member rotatable on a vertical axis and adapted to cooperate with flexible feeding means, and driving gearing for said feed operating member including parallel hori- 130

zontally disposed fast and slow speed worms, and coaxially arranged worm gears meshing therewith and rotatable on vertical axes.

- 5 54. In a mining machine, a horizontal motor having its axis extending longitudinally of the machine, cutting mechanism driven from one end of said motor, and feeding mechanism driven from the opposite 10 end of said motor including a feed operating member rotatable on a vertical axis and adapted to cooperate with flexible feeding means, and driving gearing for said feed operating member including parallel horizontal 15 axes, coaxially disposed fast and slow speed worms and coaxially arranged worm gears meshing therewith and rotatable on vertical axes, a terminal driving gear driven by said worm gearing at a plurality of speeds, and a gear 20 rotatable with said feed operating member and meshing with said terminal gear.

55. In a mining machine, a motor, cutting mechanism driven thereby, and feeding means driven by said motor including a feed 25 operating member rotatable on a vertical axis and adapted to cooperate with flexible feeding means, and plural speed driving gearing for said feed operating member including parallel worms rotatable on horizontal 30 axes, coaxially arranged worm gears meshing with said worms, and a friction clutch individual to each worm gear for controlling rotation thereof.

56. In a mining machine, a motor, cutting 35 mechanism driven thereby, and feeding means driven by said motor including a feed operating member rotatable on a vertical axis and adapted to cooperate with flexible feeding means, and plural speed driving 40 gearing for said feed operating member including parallel worms rotatable on horizontal axes, coaxially arranged worm gears meshing with said worms, a friction clutch individual to each worm gear for controlling 45 rotation thereof, a terminal gear arranged coaxially with said worm gears and driven thereby at a plurality of speeds, and a gear rotatable with said feed operating member and meshing with said terminal gear.

- 50 57. In a mining machine, a frame slidable on its bottom on the mine bottom, a motor carried thereby, and feeding means driven by said motor for feeding the machine bodily laterally over the mine bottom comprising 55 a feed operating member disposed on a vertical axis and adapted to cooperate with flexible feeding means, and means for connecting said motor to said feed operating member to drive the latter including epicyclic reduction gearing disposed with its axis of orbital movement parallel to the axis of said feed operating member and in the central longitudinal vertical plane of the machine.

- 60 65 58. In a mining machine, a frame 1141

on its bottom on the mine bottom, a motor carried thereby, and feeding means driven by said motor for feeding the machine bodily laterally over the mine bottom comprising a feed operating member rotatable on a vertical axis and adapted to cooperate with flexible feeding means, means for connecting said motor to said feed operating member to drive the latter including epicyclic reduction gearing disposed with its axis of orbital movement parallel to the axis of said feed operating member and in the central longitudinal vertical plane of the machine, and means for actuating a plurality of elements of said epicyclic gearing to produce a plural speed operation of said feed operating member.

59. In a mining machine, a frame slidable on its bottom on the mine bottom, a motor carried thereby, feeding means driven by 85 said motor for feeding the machine bodily laterally over the mine bottom including a feed operating member rotating on a vertical axis in the central longitudinal vertical plane of the machine and adapted to cooperate with flexible feeding means, and means for connecting said motor to said feed operating member to drive the latter including epicyclic reduction gearing disposed with its axis of orbital movement parallel 90 to the axis of said feed operating member and in the central longitudinal vertical plane of the machine.

60. In a mining machine, a frame slidable on its bottom on the mine bottom, a motor 100 carried thereby, feeding means driven by said motor for feeding the machine bodily laterally over the mine bottom including a feed operating member rotating on a vertical axis in the central longitudinal vertical 105 plane of the machine and adapted to cooperate with flexible feeding means, and means for connecting said motor to said feed operating member to drive the latter including epicyclic reduction gearing disposed with its axis of orbital movement parallel 110 to the axis of said feed operating member and in the central longitudinal vertical plane of the machine, and means for actuating a plurality of elements of said epicyclic 115 gearing to produce a plural speed operation of said feed operating member.

61. In a mining machine, a frame slidable on its bottom on the mine bottom, a horizontal motor carried thereby having its axis 120 extending longitudinally of the machine, cutting mechanism driven from one end of said motor, and feeding means driven from the opposite end of said motor for feeding the machine bodily laterally over the mine 125 bottom comprising a feed operating member rotating on a vertical axis in the central longitudinal vertical plane of the machine and adapted to cooperate directly with flexible feeding means, and means for connect- 130

ing said motor to said feed operating member to drive the latter including epicyclic reduction gearing disposed with its axis of orbital movement vertical and in the central 5 longitudinal vertical plane of the machine.

62. In a mining machine, a frame slidable on its bottom on the mine bottom, a horizontal motor carried thereby having its axis extending longitudinally of the machine, 10 cutting mechanism driven from one end of said motor, and feeding means driven from the opposite end of said motor for feeding the machine bodily laterally over the mine bottom comprising a feed operating member 15 rotating on a vertical axis in the central longitudinal vertical plane of the machine and adapted to cooperate directly with flexible feeding means, and means for connecting said motor to said feed operating member 20 to drive the latter including epicyclic reduction gearing disposed with its axis of orbital movement vertical and in the central longitudinal vertical plane of the machine, and means for actuating a plurality of elements of said epicyclic gearing to produce 25 a plural speed operation of said feed operating member.

63. In a mining machine, a frame slidable on its bottom on the mine bottom, a horizontal motor carried thereby having its power shaft extending longitudinally of the machine, cutting mechanism driven from one end of said motor, and feeding means driven from the opposite end of said motor for 30 feeding the machine bodily laterally over the mine bottom comprising a feed drum rotatable on a vertical axis disposed substantially midway between the sides of the machine and of a diameter substantially equal to 35 the width of the machine, a flexible feeding element cooperating with said drum, and driving connections between said motor and drum including a plural speed planetary device disposed with its axis of orbital movement 40 vertical and having frictional controlling means for each of its speeds.

64. In a mining machine, a frame slid- 45 able on its bottom on the mine bottom, a horizontal motor carried thereby having its axis extending longitudinally of the machine, cutting mechanism driven from one end of said motor including a horizontally swingable cutter bar, and feeding means driven from the opposite end of said motor 50 including a feed operating member rotatable on a vertical axis and adapted to cooperate with flexible feeding means, and plural speed driving means for said feed operating member comprising a planetary variable speed device having its axis of orbital movement 55 vertical. 60

65. In a mining machine, a frame slid- 65 able on its bottom on the mine bottom, a horizontal motor carried thereby having its axis extending longitudinally of the ma-

chine, cutting mechanism driven from one end of said motor including a horizontally swingable cutter bar, and feeding means driven from the opposite end of said motor including a feed operating member rotatable 70 on a vertical axis and adapted to cooperate with flexible feeding means, and plural speed driving means for said feed operating member comprising a planetary variable speed device having its axis of orbital movement vertical and disposed bodily between 75 the drum axis and said motor.

66. In a mining machine, a frame slid- 80 able on its bottom on the mine bottom, a horizontal motor carried thereby having its axis extending longitudinally of the machine, cutting mechanism driven from one end of said motor, and feeding means driven from the opposite end of said motor for feeding the machine bodily laterally over 85 the mine bottom comprising plural speed transmission means including a variable speed planetary device disposed with its axis of orbital movement vertical, and a feed operating member driven thereby and adapted 90 to cooperate with flexible feeding means.

67. In a mining machine, a frame slid- 95 able on its bottom on the mine bottom, a horizontal motor carried thereby having its axis extending longitudinally of the ma- 100 chine, cutting mechanism driven from one end of said motor, and feeding means driven from the opposite end of said motor for feeding the machine bodily laterally over the mine bottom comprising plural speed transmission means including a variable speed planetary device disposed with its axis of orbital movement vertical, and a feed operating member driven thereby rotatable on a vertical axis and adapted to cooperate with 105 flexible feeding means.

68. In a mining machine, a frame slid- 110 able on its bottom on the mine bottom, a horizontal motor carried thereby having its axis extending longitudinally of the ma- 115 chine, cutting mechanism driven from one end of said motor including a pivoted cutter bar disposable at either side of the frame and lengthwise of said frame, and feeding means driven from the opposite end of said 120 motor for feeding the machine bodily laterally over the mine bottom comprising plural speed transmission means including a variable speed planetary device disposed with its axis of orbital movement vertical, and a feed operating member driven thereby and adapted to cooperate with flexible feeding means.

69. In a mining machine, a frame slid- 125 able on its bottom on the mine bottom, a horizontal motor carried thereby having its axis extending longitudinally of the machine, cutting mechanism driven from one end of said motor, and feeding means driven from the opposite end of said motor for 130

feeding the machine bodily laterally over the mine bottom comprising a plural speed transmission mechanism including coaxial fast and slow speed friction controlling 5 clutches and a feed operating member driven thereby and rotatable on a vertical axis and adapted to cooperate with flexible feeding means.

70. In a mining machine, a frame 10 slideable on its bottom on the mine bottom, a horizontal driving motor carried thereby having its axis extending longitudinally of the machine, cutting mechanism driven from one end of said motor, and feeding means 15 driven from the opposite end of said motor for feeding the machine bodily laterally over the mine bottom comprising a plural speed transmission mechanism including coaxial fast and slow speed worm gears and a 20 feed operating member driven thereby and adapted to cooperate with flexible feeding means.

71. In a mining machine, an invertible machine frame slideable on the mine bottom 25 and having a plurality of opposed plane surfaces on which the machine is adapted to be selectively supported during its operation, a motor carried by said frame, and feeding mechanism driven by said motor for 30 feeding the machine bodily laterally over the mine bottom while supported on either of its supporting surfaces including a feed operating member rotatable on a vertical axis perpendicular to said plane supporting surfaces and adapted to cooperate with flexible 35 feeding means.

72. In a mining machine, a machine frame slideable on the mine bottom and having a plurality of opposed plane surfaces on which 40 the machine is adapted to be selectively supported to enable the machine to cut in different planes, a motor carried by said frame, cutting mechanism including a horizontal plane cutter bar, and feeding mechanism 45 driven by said motor for feeding the machine bodily laterally over the mine bottom while supported on either surface including a feed operating member rotatable on a vertical axis perpendicular to said plane supporting surfaces and adapted to cooperate 50 with flexible feeding means.

73. In a mining machine, a frame slideable on its bottom over the mine bottom and including a horizontal motor having its axis 55 extending longitudinally of the machine, cutting mechanism driven from one end of said motor, and feeding mechanism driven from the opposite end of said motor including plural speed gearing, certain of the gears 60 of which are coaxially arranged and rotatable on vertical axes and each having individual frictional controlling means, and a feed operating member driven thereby rotatable on a vertical axis and adapted to 65 cooperate with flexible feeding means.

74. In a mining apparatus, a machine frame slideable over the mine bottom on its bottom and having a projecting cutter bar, a feed operating member and adapted to cooperate directly with flexible feeding means 70 rotatable on an axis perpendicular to the plane of operation of said bar, a driving member for said feed operating member transmitting rotation thereto and rotatable on an axis parallel to the axis of the latter, and driving means for said driving member including a worm rotatable on an axis extending longitudinally of said frame and a manually controllable friction clutch coaxial with said worm for controlling driving of 80 the latter.

75. In a mining machine, a machine frame slideable on its bottom on the mine bottom, a motor carried thereby and having its power shaft extending longitudinally of the machine, cutting mechanism driven from one end of said motor, and feeding mechanism including a feed operating member adapted to cooperate with flexible feeding means, and plural speed driving connections between said 90 feed operating member and the opposite end of said motor including coaxial fast and slow speed worm wheels rotatable on a vertical axis and selectively operable to drive said feed operating member at fast and slow 95 speeds.

76. In a mining machine, a machine frame slideable on its bottom on the mine bottom, a motor carried thereby and having its power shaft extending longitudinally of the machine, cutting mechanism driven from one end of said motor, and feeding mechanism including a feed operating member adapted to cooperate with flexible feeding means, and plural speed driving connections between 100 said feed operating member and the opposite end of said motor including coaxial fast and slow speed worm wheels rotatable on a vertical axis and selectively operable to drive said feed operating member at fast and slow 105 speeds, and worms rotating on parallel axes and meshing with said worm wheels respectively.

77. In a mining machine of the type slideable on its bottom on a mine bottom during cutting, feed operating mechanism including a feed operating member adapted to cooperate with flexible feeding means, a motor, cutting mechanism driven from one end of said motor, and plural speed driving connections between said feed operating member and the opposite end of said motor including coaxial fast and slow speed worm wheels rotatable on a vertical axis and selectively operable to drive said member at a 115 plurality of speeds.

78. In a mining apparatus, in combination, a machine frame slideable on its bottom on the mine bottom, feeding mechanism carried thereby including a feed operating mem- 120

ber rotatable on a vertical axis and adapted to cooperate directly with flexible feeding means and actuating means for said member including a plurality of coaxial worm 5 wheels disposed on axes parallel to a line parallel to the axis of rotation of said feed operating member, means whereby said feed operating member may be driven by either of said worm wheels, and means for effect- 10 ing rotation of said worm wheels at different speeds including worms engaging respectively therewith and rotating on parallel axes.

79. In a mining apparatus, in combination, a machine frame slidable on its bottom 15 on the mine bottom, feeding mechanism carried thereby including a feed operating member rotatable on a vertical axis and adapted to cooperate with flexible feeding means, actuating means for said feed operating 20 member including a plurality of coaxial worm wheels rotatable on axes parallel to a line parallel to the axis of rotation of said feed operating member, means whereby said feed operating member may be driven by

either of said worm wheels, and means for 25 effecting rotation of said worm wheels at different speeds including oppositely rotat- ing worms engaging respectively therewith.

80. In a mining apparatus, in combina- 30 tion, a machine frame slidable on its bottom on the mine bottom, feeding mechanism carried thereby including a feed operating mem- ber rotatable on a vertical axis and adapted to cooperate directly with flexible feeding means and actuating means for said feed 35 operating member including a plurality of coaxial worm wheels rotatable on axes parallel to a line parallel to the axis of rotation of said feed operating member, means whereby said feed operating member may be driven 40 by either of said worm wheels, and means for effecting rotation of said worm wheels at different speeds including worms engag- ing respectively therewith and rotating in opposite directions on parallel axes. 45

In testimony whereof I affix my signature.

MORRIS P. HOLMES.
